UNITED STATES PATENT OFFICE

2,324,478

APPARATUS FOR STRIPING ROADWAYS

Purling A. Bleakley, Toledo, Ohio, and Tennies F. Kolts, Chicago, Ill.

Application January 31, 1940, Serial No. 316,502

4 Claims. (Cl. 91—12)

Our invention relates to improvements in apparatus for striping roadways and is particularly concerned with the provision of a highly efficient mobile unit which is capable of high speed application of the stripes or lines so generally employed at the present time in dividing roadways, boulevards, etc., into two or more lanes.

An object of our invention is the provision of efficient means for projecting metal or alloys thereof in molten comminuted form, onto the surface of a roadway, for example, in such fashion that the metal or alloy effectively adheres to the surface.

Another object of the invention is the provision of novel means for regulably controlling the manner in which the metal or alloy is projected. To this end we have provided means for controlling the cross-sectional form of the stream of material projected and additional means for regulably controlling the width of the stripe or ribbon that is applied to the road or other surface.

A further object is the provision of a mobile apparatus including a metal projecting gun which is of such character that the metal, during projection thereof onto the road or other surface, travels through a non-oxidizing atmosphere. Thus the metal, aluminum, or alloys consisting largely of aluminum, will not oxidize and for this reason effectively adheres to the surface. In the absence of provision against oxidation, the particles of metal would not satisfactorily bond together and any bond or adherence to the surface would be weak and quite irregular and spotty.

A still further object is the provision of novel means for preparing the surface to be coated. To this end a high speed rotary brush cleans the road surface in advance of the metal projecting gun, the brush and gun both being mounted upon a common support.

It is also an object of our invention to provide means for manually adjusting the gun, brush and means for controlling the width of the applied stripes, transversely of a truck or other mobile carrier whereby to compensate for variations in arc described by the carrier in following curves and turning corners in the roadway. For this purpose all of the elements aforesaid are adjustable as a unit.

It is likewise an object of our invention to provide a completely mobile unit in which the projecting gun, air compressor, gas tanks and all accessory equipment are conveniently arranged and readily removable and replaceable when necessary.

Another important feature of our invention is the provision of means for predetermining the width of the applied stripe, including high speed rotary disks which define the transverse width of the stream of metal substantially at its point of impingement against the road surface.

Other objects will be in part apparent and in part pointed out hereinafter.

In the drawings forming a part of our application and throughout which like reference characters are employed to designate like parts:

Fig. 1 is a side elevational view of a motor driven truck embodying our invention.

Fig. 2 is a top plan view thereof with a portion of the roof removed to expose the road striping mechanism.

Fig. 3 is a fragmentary side elevational view illustrating in detail, the striping mechanism.

Fig. 4 is a sectional view on the line 4—4 of Fig. 3.

Fig. 5 is a sectional view on the line 5—5 of Fig. 3.

Fig. 6 is a sectional view on the line 6—6 of Fig. 3.

Fig. 7 is a sectional view on the line 7—7 of Fig. 4.

Fig. 8 is a fragmentary elevational view of a surface preparing wheel.

Fig. 9 is a rear elevational view of the mechanism for defining the area to be striped.

Fig. 10 is a sectional elevational view of the mechanism disclosed in Fig. 9, taken along the line 10—10 of Fig. 3.

Fig. 11 is an elevational view taken along the line 11—11 of Fig. 3.

Fig. 12 is a perspective view of a pilot or indicator rod which is mounted at the front end of the truck.

Fig. 13 is a wire diagram of a system employed for automatically interrupting the striping operation at regular time intervals.

Fig. 14 is a vertical sectional view showing auxiliary disks for directing metal to the desired surface area.

Fig. 15 is a side elevation of a modified arrangement of a gun and margin wheels.

Fig. 16 is a sectional view on line 16—16 of Fig. 15.

Fig. 17 is a sectional view on the line 17—17 of Fig. 15.

In the illustrated embodiment of our invention, it is mounted upon the chassis C of a motor truck M. Briefly the apparatus (Figs. 1 and 2) includes a metal projecting gun 20, a surface preparing unit 21, a deflector unit 22 for gauging or de-

fining the area to be striped and, if desired, a polishing unit 23, said gun and units being so interconnected that all may be adjusted simultaneously transversely of the truck and thereby regularly control the zone in which the metal stripe is applied by the gun 20. The surface preparing unit may assume the form of a motor driven brush 24 (Fig. 6) or may consist of a wheel 25 (Fig. 8) having sharp projections 25a or teeth which break through the glazed surface of brick paving, for example. The gun 20 which embodies the principles and many details of the apparatus disclosed in Bleakley Patent #2,092,150 issued September 7, 1937, projects metal or alloys thereof in molten comminuted form onto the road surface, the area to which it is applied being determined by the gauging or deflector unit 22. The applied stripe may, if desired, be polished by the polishing unit 23. All of the above units are longitudinally aligned with a pilot or guide rod 26 which is mounted at the inner end of the front bumper B, the lower end of the rod being visible to the truck driver through a transparent sheet 27, glass for example, in a sight opening 28 in the left front fender F. This pilot rod is maintained in register with a previously formed guide line and as a result, the gun necessarily is in register therewith except on curves where it is necessary for an attendant to move the gun and parts connected thereto transversely of the truck to compensate for the change in position of the truck relative to the guide line.

Mounted upon the chassis C is a group of gas tanks 29, a compressed air tank 30 to which air is delivered by a compressor 31, and a motor generator 32 for electric current. These units are important in the operation of the gun and associated elements heretofore described as well as to the mobility of the complete apparatus as is obvious. It has been discovered that relatively cool compressed air is conducive to higher efficiency in operation of the gun and consequently the air is delivered to the gun by way of coils 33 which are cooled in any preferred manner. The coils as shown, are placed in a container 34 for a cooling medium. Metal which is comminuted and melted by the gun 20 preferably is fed in wire form from a coil 35 which is mounted in proximity to said gun.

The metal projecting gun 20 (Figs. 1, 2, 3, and 11) consists of a barrel 36 mounted upon and depending from, a frame 37 which frame also carries an electric motor 38 (Fig. 2). This motor actuates wire feeding means 39 which are shown in the form of frusto-conical rollers having corrugated faces designed for effectively gripping the wire W. At one side of this frame is a valve box 40 in which four valves 41 provide for regulable control of the delivery of air, oxygen, acetylene gas and a neutral gas to the gun through the pipes shown. The delivery of these fuels and function thereof etc., are identical to the disclosure in the above noted Bleakley patent to which reference may be made for complete details. The neutral gas is controlled by a valve and flows through a pipe 42 to the gun. This gas produces a blanket at and for a distance beyond the gun nozzle and prevents oxidation of the projected metal, aluminum, for example by consuming substantially all of the oxygen in the atmosphere through which the metal is projected onto the road surface. This neutral gas is also employed to flatten the projected stream of molten comminuted metal that is projected onto the road surface. To this end, jets 43 are arranged upon

opposite sides of the gun nozzle slightly outwardly thereof and are connected through short conduits 44 to the aforementioned neutral gas pipe 42. A valve 45 is placed in this pipe 44. Thus it has been discovered, the two sheets of gas projected under relatively high pressure, effectively flatten the stream of metal and bring about an improved coating operation including, among other advantages, the production of a coating of uniform thickness. This gas ignites upon contact with the burning gas that produces the blanket referred to above.

Returning again to the gun mounting, it will be noted (Figs. 1, 2, 3) that a gun supporting arm 46 is pivoted at its outer end to the frame 37 and at its inner end (Figs. 2, 3, and 4) is hinged to and for vertical adjustment about the axis of a horizontal rock shaft 47. The angular relationship between the gun and said arm 46 is controlled by an adjusting rod 46a and set screw 46b. This shaft 47 is journaled in a bearing 48, (Figs. 3 and 4) at the upper end of a frame 49 rising from a shelf 50 which is carried by the chassis C of the truck. Rocking of the shaft 47 for the purpose of changing the angular position of the gun 20 is obtained by mechanism including a worm gear 51 on said shaft running in mesh with a worm 52. A hand wheel 53 is operatively connected to the worm and provides means for manually adjusting the angular position of the gun. A housing 54 encloses the worm and worm gear.

Transverse adjustment of the gun relative to the truck is obtained by manual rotation of a hand wheel 55 which is disposed below the wheel 53 for changing the angle of the gun, the former wheel being attached to a horizontal shaft 56 which is journaled in bearings 57 in the slide frame 58. A pinion 59 on the shaft 56 meshes with a rack bar 60 which is fixed to the lower side of the bearing 48 for the gun arm 46. This bearing (Fig. 7) carries rollers 61 which run in ways 62 at the upper end of the frame 49. An arm 63 extending outwardly from the outer end of the base of the bearing carries an elongated frame 64. This frame 64 extends forwardly and rearwardly of the gun position and at its forward end, supports the aforementioned surface preparing unit 21 and at the rear end supports the polishing unit 23 should this unit be employed. The stripe gauging unit 22 is also mounted at the rear end of said frame 64.

The surface preparing unit 21 (Figs. 1, 2, 3, 5, and 6) comprises a rotary brush 24, or in some instances, a guiding wheel 25 (Fig. 8) mounted removably, upon a shaft 65 which is enclosed in a housing with meshing bevel gears 66 through which power is transmitted to the brush from a drive shaft 67. This drive shaft 67 is enclosed in a tubular housing 68 and is connected to the shaft of an electric motor 69. This motor and the tubular housing 68 are rigidly mounted upon a frame 70 which is shown to be substantially reverse L-shaped, the base 71 of which is journaled in opposed horizontal bearings 72. These bearings form part of a U-shaped frame 73 which is connected through an arm 74 to the aforementioned elongated frame 64, and is directly supported by a slide 75. This slide is mounted in slideways 76 on a shelf 77 which projects outwardly from one side of the chassis C. A counterbalancing spring 78 connects one of the slideways 76 and the motor 69 for obvious reasons.

The polishing unit 23 may well be of the same construction as the gauging unit 21 and is so shown. The polishing wheel 79 is mounted at the

lower end of the shaft housing 80 which at its upper end is connected to a hinged motor frame 81. The motor is similar to the other motor 69, each of these motors and the motor 38 on the gun having a starter switch S. The motor frame 81 is hinged upon pivot pins 82 which form part of a frame 83 rising from a slide 84, the latter riding in slideways 85 on the shelf 50 which projects outwardly from the chassis C as heretofore described in connection with the gun mounting. An arm 86 which is also carried by the frame 83 is hingedly connected to the gauging unit 22.

This gauging unit as indicated heretofore, defines the margins of the area to be striped and definitely prevents the coating material from spreading beyond the desired line. The structure comprises an elongated U-shaped frame 87 pivoted by hinge pins 88 to the aforementioned arm 86. A forwardly extending horizontal frame 89 carries a pair of bearings 90 at its rear end, through which bearings, extends a shaft 91, the latter pivotally connecting the two frames 87 and 89 and having driving connection to a ground engaging traction or driving wheel 92 from which power is obtained and transmitted through sprockets 93 on said shaft, and chains 94 and additional sprockets 95 at the front end of the frame 89 to disks 96. These disks 96 are journaled upon shafts 97 (Fig. 3) to which the aforementioned sprockets 95 are attached. Scrapers 98 for removing accumulated metal from the disks 96 are attached to the frame 89 through arms 99. A coil spring 100 tends to advance the frame and disks relative to the gun and an adjustable set screw 101 in cooperation with a stop 102 formed by a part of the chassis C, limits such forward movement. Together these devices constitute a convenient means for adjusting the relation between the gun and disks.

In Fig. 12, we have illustrated the pilot rod mounting which consists simply of a horizontal supporting rod 103 rockably mounted in a bracket 104 on the bumper B. The outer end of this supporting rod has a vertical eye 105 through which the pilot rod 26 extends. A set screw 106 secures the pilot rod at any adjusted point and a set screw 107 holds the two rods at such a position that the lower end of the pilot rod may be visible to the truck driver through the sight opening in the fender F. A flexible extension 108 is secured to the lower end of the pilot rod to prevent breaking of the rod proper should it strike an obstacle in the roadway.

In Fig. 13 we have shown a wiring diagram of a circuit for controlling the operation of the motor 38 which feeds the wire through the gun. The circuit may include in addition to the main switch 109, a time relay 110 which at regular time intervals, shuts off the motor and thereby interrupts the feeding of wire to the gun. Thus a broken line may be produced on the road surface, if desired.

In Fig. 14 an auxiliary disk 111 is mounted inwardly of the main disk 96 and has driving connection through the shaft 112 to a sprocket 113 which corresponds to the aforementioned sprocket 95 at the forward end of the horizontal frame 89. The sprocket ratio may be such that the disk 111, of which there would be two, would rotate at a relatively high speed and reduce any tendency on the part of the molten metal to adhere thereto. Cooling of the gauging disks to minimize the adhesion of metal thereto is obtained by spraying water or other cooling medium from supply pipes 114 which are connected to any suitable source.

In view of the outline of the operation earlier in this description, only a brief reference thereto would appear to be necessary. It will be understood that in striping straight stretches of roadway, the truck driver need merely keep the pilot rod in register with a previously formed or old line in order to be assured of proper positioning of the gun and associated parts. The gun projects the molten comminuted metal or alloy onto the selected area and as defined by the gauging disks. Prior to the coating operation, the surface to be striped is cleaned and slightly roughened by the brush 24 or wheel 25. As stated heretofore, the polishing wheel 79 may be employed if circumstances appear to warrant its use. Upon reaching and rounding a curve, it is necessary to move the gun and with it the parts connected thereto, transversely of the truck to compensate for the change in the relative positions of the preformed line and point of location of the gun on the truck. This is controlled manually by an operator. Our apparatus has demonstrated its adaptability to the production of stripes or lines of uniform width and depth at a comparatively high speed. The coating material firmly bonds with the road material and further provides a readily visible surface which, when formed of aluminum or an alloy thereof, is highly reflective.

Figs. 16-17 inclusive show a modified form of gun and margin wheels which may be employed and which are found to give results even superior to the arrangement shown in the preceding figures. In this instance, the gun is supported on the truck in a vertical position and is attached thereto in any suitable manner so that it may be lowered or raised relatively to the road surface and so that it may also be moved laterally of the road when the truck is proceeding around a curve.

In this modification the gun shown in the Bleakley Patent No. 2,092,150 may be employed but some other gun producing substantially the same effect may be used. The gun itself is secured directly to a suitable and simple mechanism (not shown) for raising or lowering or for moving the gun transversely. A bracket 116 is mounted in a swivel manner upon the gun 115 by means of a pair of collars 117 and 118 for supporting just below the nozzle 119 a pair of margin or masking disks 121 and 122 rotatably carried on arms 123 and 124 secured to the bracket 116. The swivel mounting of the bracket 116 enables the operator to rotate the entire disk assembly about the gun should this be necessary at any time, as for example, when working on a sharp curve.

A pair of nozzles 125 and 126 are positioned and connected to a suitable supply tank to provide jets of gas which will be ignited when projected to surround the conical stream of molten metal with an enveloping blanket of non-oxidizing gas, or products of combustion. Such a gas may be propane, butane, propylene or any of the commonly available mixtures of them or such other hydrocarbon gases as are now sold in bottled form. These burning gases will not only exclude the atmospheric oxygen from contact with the molten metal to save the latter from oxidation, but they will also aid in maintaining the temperature of the metal until it contacts the roadway to which it must be bonded while still molten. It is such gas as is referred to hereinbefore as a neutral gas and, as explained above, the force of the gas jets tends to shape the cone

of projected metal and confine it within the space defined by the disks 121 and 122.

As shown in Fig. 17, these disks are provided with water jackets 127 and 128 into which streams of water may be introduced to prevent the disks from becoming overheated to an extent that might invite adherence of the molten metal. The surplus of water is permitted to escape from the water jackets through annular apertures in the jackets surrounding the hubs 129 and 131 which support shafts 132 and 133 of the disks. These hubs are formed on the lower ends of the arms 123 and 124 secured to the supporting bracket 116. Any suitable means for supplying water to the water jackets may be employed. We have shown for that purpose tubes 134 and 135 which may be connected on the truck.

A spray of molten metal when projected vertically, as herein described and thereafter solidified on the pavement is found to present minute reflecting surfaces which are equally visible and effective when viewed and lighted from either direction of vehicle traffic. When the molten metal is projected in an inclined stream as from the gun positioned as shown in Fig. 3, the reflecting surfaces from the hardened metal stripe are found to be more effective when viewed from one direction than they are from the other direction of vehicle traffic, which may well be satisfactory for some purposes. The vertical mounting of the gun results in equalizing the reflective properties of the finished stripe, which we have discovered to be in general more desirable.

In connection with this modification of the invention it is preferred not to use the polishing brush after the stripe is laid. In fact we find that the metal coats the irregularities of the roadway to thus produce reflective surfaces which should not be polished.

It is apparent that the water jackets on the disks provide more effective cooling than is obtained through the spraying of water jets upon the outsides of the disks, as illustrated in Fig. 10. As shown in Fig. 17, these water jackets have a smaller diameter than the disks, hence they do not interfere with the contact of the disks with the road. Because of ample cooling by water these disks do not need to be rotated rapidly, consequently, they are rotated merely by their contact with the roadway.

We have found that the jets of gas which form the enveloping non-oxidizing blanket are most effective for distorting a vertically projected metal spray from its natural conical form into somewhat elliptical form of symmetrical cross section. A stripe of substantially uniform thickness may thus be deposited. The width of the spray along its major elliptical axis is so regulated that some of the metal will strike the oppositely facing masking disks and slide down them. Due, however, to the water cooling of the disks the molten metal will not adhere thereto. The temperature of the molten metal at the time all of it reaches the road surface is maintained so high that the metal particles become bonded to the road surface and to each other while still in molten condition. By thus maintaining the temperature of the metal and by preventing any substantial oxidation, the stripe laid down is firmly bonded and free from metal in flake or powder form.

We have found that when the metal is applied as herein described and consists of aluminum or an alloy largely consisting of aluminum, the metal when it solidifies has brilliant light color in contrast to the dull appearance

typical of ordinary cast and spun aluminum articles. Not only is the finished surface almost white in color but the surface is studded with a myriad of minute irregularities which are found to be ideal for reflecting light rays whether under daylight or night-driving conditions. The surface of the stripe is found to remain unimpaired even where subjected to the severest traffic and weather conditions.

Not only is it an object of the invention to deposit on the roadway a stripe having the hereinbefore specified color and reflective characteristics and uniform thickness but it is particularly desirable that precautions be exercised to prevent the depositing of a stripe of excessive thickness even though it may be uniform. We have found that if the truck on which the apparatus is mounted be temporarily slowed down below the calculated desired speed, the gun will continue to deposit metal at the same speed per unit of time and the stripe will therefore be built up to an exceptional thickness. While some variation in thickness is permissible, yet, a stripe that is too thick will not remain bonded to the pavement. The irregularity in expansion between a thick layer of the metal and the road surface, together with the exceptional pounding which a thick layer might receive will eventually cause a stripe of excessive thickness to peel from the pavement. The general object of this invention, that is, the laying down of stripes that do not require continued or frequent maintenance, would thereby be defeated.

Accordingly, in connection with the operation of the gun and associated apparatus as described above, we propose to control the speed of the truck with a high degree of uniformity in order that any desired calculated speed may be accurately maintained.

One method which we employ is to indicate the engine speed on a tachometer and have the operator manually control the speed of the truck to show a constant tachometer reading.

In place of this manual control we may also employ any well-known form of automatic governor control.

For example, if it be desired to deposit a stripe $4\frac{1}{2}$ inches wide and $\frac{3}{1000}$ of an inch thick and the assumed capacity of the gun for melting aluminum be 33 lbs. per hour, the rate at which the aluminum will be delivered by the gun will be considered as constant due to the practical impossibility of varying the output of such guns, it being understood that they operate most satisfactorily only at maximum output. With the output of the gun known it is then a matter of calculation to determine the approximate rate at which the truck should move in order to deposit the aluminum in a layer of the desired thickness. In the present example, the truck should be propelled uniformly at the speed of about 2400 feet per hour. The exact speed, of course, should be determined with reference to the actual operating condition of the gun and the condition of the road surface on which the layer of metal is being deposited.

It should be understood that the invention is not limited to the special details herein described, but includes numerous variations and modifications which nevertheless are comprehended within the scope of the invention defined in the appended claims.

We claim:

1. In apparatus for stripping roadways, mobile means for projecting a spray of molten metal

in comminuted form onto the area to be striped, means including a pair of horizontally spaced rotary disks mounted in substantially horizontal bearings for intercepting and deflecting the lateral portions of said spray for defining the margins of said area, and means for positively directing a stream of cooling fluid onto each of said disks.

2. In apparatus of the character described, a metal projecting gun, a slideable bearing, a rock shaft in the bearing, an arm pivoted at one end to the gun and at its other end secured to said shaft, means for adjusting the angular relationship between said gun and arm, means for adjusting both the gun and arm about the axis of said shaft and means for moving the gun, arm, bearing and shaft axially of the latter.

3. In apparatus of the character described, a metal projecting gun, a slideable bearing, a rock shaft in the bearing, an arm pivoted at one end

to the gun and at its other end secured to said shaft, means for adjusting the angular relationship between said gun and arm, means for adjusting both the gun and arm about the axis of said shaft, and means for moving the gun, arm, bearing and shaft axially of the latter including means slidingly supporting the bearing, a rack bar on the lower side of the bearing, a pinion meshing with the rack, and manually operable means for rotating the pinion.

4. In a road striping apparatus, a metal projecting gun, a mobile carrier therefor, an electric motor driven wire feeder for propelling a wire through the gun, a control means for periodically and automatically interrupting operation of the feeder whereby to produce breaks in the applied stripe.

20

PURLING A. BLEAKLEY.
